UNITED STATES PATENT OFFICE.

JOSEPH C. HOULEY AND CHARLES E. SHAW, OF CHICAGO, ILLINOIS.

PHONOGRAPH-CABINET.

1,378,117.

Specification of Letters Patent. Patented May 17, 1921.

Application filed September 21, 1920. Serial No. 411,794.

To all whom it may concern:

Be it known that we, JOSEPH C. HOULEY and CHARLES E. SHAW, citizens of the United States, residing at Chicago, in the county of Cook and State of Illinois, have invented new and useful Improvements in Phonograph-Cabinets, of which the following is a specification.

This invention relates to filing devices designed for use in connection with talking machine record disks, and its object is to provide a novel and improved device of this kind consisting of a series of slidable record-supporting shelves, and means whereby a shelf containing the desired record may be placed in a position for enabling the record to be readily removed therefrom.

The object stated is attained by means of a combination and arrangement of parts to be hereinafter described and claimed, and in order that the same may be better understood, reference is had to the accompanying drawing forming a part of this specification.

In the drawing,

25 Figure 1 is a plan view of the device, partly broken away.

Fig. 2 is a front elevation, and

Fig. 3 is a rear elevation partly broken away.

30 In carrying out the invention, there is provided a frame or inclosure carrying a series of vertically spaced horizontally slidable shelves 10 on which the talking machine record disks 11 are supported, each 35 shelf carrying one disk.

The frame or inclosure is composed of side walls 12 rigidly secured to and rising to a suitable height from a base plate 13, with a top cross strip 14 connecting said 40 walls at the rear, and a cross strip 15 at the front. The strip 15 is secured to the front edges of the walls 12, and it extends downwardly for a short distance, leaving the remainder of the inclosure, down to the base 45 plate 13, open, so that the shelves 10 may be slid forwardly to project from the front opening thus formed in the inclosure. To the rear edges of the walls 12 are also secured vertical brace strips 16, which do not 50 extend entirely across the back of the inclosure, leaving the same open between the said strips.

Inside the inclosure, the side walls 12 carry front and rear angle irons 17 arranged 55 so that one of the flanges of each projects inwardly, and these projecting flanges have

edge notches 18 in which the shelves 10 slidably seat at their side edge portions.

Back of the shelves 10, are located two upright posts 19 which extend between the base plate 13 and the rear top cross strip 14, and are suitably secured thereto. On each post 19 is fulcrumed a series of levers 20, each of which is connected to a shelf 10, the rear edge of the latter carrying a rearwardly projecting apertured flange 21 into the aperture of which one end of the lever loosely extends. The other ends of the levers 20 are connected, as shown at 22, to push rods 23 extending along the side walls 70 12, on the inside of the inclosure, and projecting from the front thereof, and being here fitted with a button 24 suitably numbered or inscribed with any other index mark. The rods 23 are supported by the 75 outstanding flanges of the angle irons 17, the same having apertures in which the rods slidably seat.

Each shelf 10 is provided with an actuating connection consisting of a lever 20 and an operating rod 23, and hence by pressing in on the button 24 denoting the desired shelf 10, the latter is advanced from the open front of the inclosure such a distance that the record 11 carried thereby can be 85 readily grasped and removed. It will be understood of course that the records will be filed away on the shelves in the same order they appear on a list containing the titles of the selections and identifying numbers. Thus, by consulting the list, any desired record may be readily removed from the inclosure by pressing on the button containing the same number as that associated with the title of the selection as it appears 90 on the list. To return the record, it is placed on the advanced shelf, and the latter is pushed back into the inclosure.

On the top of each shelf 10 are guard strips 25 for the records 11, the latter seat- 100 ing between said strips.

The device provides a very simple, compact and efficient filing device, and one which can be installed in any phonograph cabinet, and in order that this may be readily done, the base board or plate 13 has its under side fitted with two flush and forwardly projecting flanges 26 by which the entire device may be secured in the cabinet by passing screws or other suitable fasteners 105 through perforations 27 in said flanges and into the floor of the cabinet. It will be 110

noted that the levers 20 on the respective sides of the device are connected to the shelves 10 in alternate order, for the purpose of reducing the space occupied thereby.

5 Some of the shelves 10 may be provided with a back stop, such as a rib 28 extending across the same near the rear edge thereof, as shown in Fig. 1. The purpose of this rib is to locate a smaller record close enough 10 to the front edge of the shelf so as to be readily accessible. Thus, the upper shelves may be designed for ten-inch records, whereas the lower shelves may hold twelve-inch records, and as all the shelves are of the 15 same size and depth, it will be seen that by the ribs 28 applied to the shelves which hold the ten-inch records, the latter are held even at their forward edges with the corresponding edges of the twelve-inch 20 records.

We claim:

1. A filing device for talking machine record disks, comprising a frame having side walls and an open front, a series of vertically spaced and horizontally slidable disk-supporting shelves between the side walls and adapted to be projected from the open front of the frame, shelf-supporting flanges 25

on the side walls, said flanges having edge notches in which the shelves seat at their 30 side edge portions, levers connected to the shelves for projecting the same, and slidable actuators for the levers supported by the aforesaid flanges and projecting from the front of the frame. 35

2. A filing device for talking machine record disks, comprising a frame having side walls and an open front, a series of vertically spaced and horizontally slidable disk-supporting shelves between the side 40 walls and adapted to be projected from the open front of the frame, shelf-supporting flanges on the side walls, said flanges having edge notches in which the shelves seat at their 45 side edge portions, upright posts mounted in the frame to the rear of the shelves, levers fulcrumed on the posts and connected to the shelves for projecting the same, and slidable actuators for the levers supported by the aforesaid flanges, and projecting from the open front of the frame. 50

In testimony whereof we affix our signatures.

JOSEPH C. HOULEY.
CHARLES E. SHAW.
